(57) **CLAIM**

The ornamental design for a modular video support frame member, as shown and described.

DESCRIPTION

FIG. 1 is a front perspective view of a modular video support frame member showing our new design;

FIG. 2 is an enlarged front perspective view of a portion of the modular video support frame member shown in FIG. 1;

FIG. 3 is an enlarged rear perspective view of a portion of the modular video support frame member shown in FIG. 1;

FIG. 4 is a front view thereof;

FIG. 5 is a top view thereof, the bottom view is a mirror image of the top view;

FIG. 6 is a right-side view thereof, the left-side view is a mirror image of the right-side view; and,

FIG. 7 is a back view thereof.
